UNITED STATES PATENT OFFICE.

ROBERT E. KLETT, OF RIDGEWOOD PARK, NEW JERSEY, ASSIGNOR TO KLETT MANUFACTURING COMPANY, INC., OF NEW YORK, N. Y., A CORPORATION OF NEW YORK.

SYRINGE.

Application filed March 12, 1920. Serial No. 365,177.

To all whom it may concern:

Be it known that I, ROBERT E. KLETT, a citizen of the United States, and a resident of Ridgewood Park, in the county of Bergen and State of New Jersey, have invented certain new and useful Improvements in Syringes, of which the following is a specification.

This invention relates to syringes and has particular reference to syringes used for medicines, wherein the working parts must be non-metallic as far as possible and of close fit without packings. These syringes are ordinarily of a glass barrel ground internally to true cylindrical form and carrying a piston either composed of a solid glass rod ground to fit the barrel or else of glass with a metallic rod, no packings being used.

Although numerous devices of such syringes are now on the market they are unsatisfactory for various reasons, among which may be mentioned the difficulty of attaching the ferrules to the barrel, the difficulty of closing the forward end carrying the nozzle, and also liability of the piston to be drawn too far back and disengaged entirely from the barrel. These syringes ordinarily carry finger holds and another difficulty is in properly attaching the finger hold to the rear end of the barrel.

By this invention a method or means is provided for attaching a ferrule to either or both ends of the barrel in such manner as to permit the forward end to be closed or the rear end to carry a finger rest with or without a movable stop for preventing the piston from being wholly withdrawn from the barrel. As is well known, these syringes are required to be frequently sterilized in boiling water, disinfectants, etc., and must be disassembled in order to permit free access of the sterilizing medium to all parts, as well as thorough cleaning.

According to this invention, the front end of the barrel is preferably closed by a glass disc fused to the end of the barrel, and within this disc is a plug having a ground fit in the barrel, both the plug and the disc being perforated to receive the nozzle which is fastened by an external nut or other means. For carrying the nozzle or adding strength at this end a metallic ferrule may be provided. At the rear end, a similar ferrule is desired, which will carry the finger

rest and also the movable latch for stopping the piston before it leaves the barrel. But a particular feature of this invention resides in the means for attaching these ferrules to the glass or other nonmetallic cylinder. This material is frequently brittle and it is difficult to make cements fasten the metal to the glass. I accomplish this result by grooving the barrel, springing a metallic band therein and providing a ferrule which will overlie the band and which can be either soldered to the band or spun down over the band, or cemented thereto, as may be preferred. This is applicable to either end. The ferrule carries a pivoted arched latch which can be swung up to embrace the reduced portion of the piston rod so as to stop the piston before it leaves the barrel, and when the piston is to be taken up the latch is swung down out of the way. The invention will be more fully understood in connection with the description of the accompanying drawings, wherein—

Figure 1 is a section of a syringe embodying the invention;

Figure 2 is an end view;

Figure 3 is a side view; and

Figure 4 is a section showing a slight modification.

1 represents the barrel, usually composed of glass, 2 the piston, preferably composed of glass but for some purposes may be composed of metal, but without a packing, both the barrel and the piston being ground to fit. 3 represents the piston rod having a handle 4. At the forward end, the barrel is sealed by a disc 5 fused therein, and within the end of the barrel adjacent the disc 5 is a plug 6 having a ground fit in the barrel. The plug 6 and disc 5 are bored to receive a discharge nozzle 7, the inner end of which is expanded to prevent the nozzle 7 from drawing outwardly through plug 6, while the outer end of nozzle 7 is secured by a nut or other fastening means 8 to prevent the nozzle 7 from being forced inwardly. To add strength a ferrule 9 may be interposed between the fastening 8 and the disc 5, and this ferrule is secured to the barrel independently of the disc 5 by means of a band 10 shrunk in a groove adjacent the end of the barrel and the ferrule 9 secured to this band, either by solder, cement, or by spinning down. The band 10 is usually in the

form of a ring made of such diameter as to slide over the barrel and contract tightly into the groove, and readily lends itself to being cemented or soldered to the ferrule. 5. Thereby a very strong construction is obtained which will withstand the pressure of the piston and the variations in temperature due to sterilizing, and the plug and nozzle can be readily taken out whenever desired. 10. At the other end, the barrel is provided with a similar groove carrying a band 10, and a ferrule 11 is similarly fastened thereon. This ferrule carries finger rests 12 and lugs 13 in which are sprung wire loops 14 having central bands 15 to embrace the rod 3. The arch of the loop 14 is made of such size as to stop the piston before it leaves the barrel, and when it is desired to withdraw the piston entirely the loops are swung 15 down, as shown in dotted lines in Figure 3, to permit this. The lugs 13 are provided with slots into which the loops spring when extended so as to hold them. One loop can be used instead of two if desired and the 20 loops can readily be detached from the lugs 13 when desired. For the purpose of fastening to the barrel, the ferrule 11 is equivalent to ferrule 9.

Figure 4 differs from Figure 1 in that the 30 ferrule at the front end is omitted and the nozzle 7 and nut 8 are of somewhat different shape.

Various modifications and changes may be 35 made without departing from the scope of the appended claims.

What I claim is:

1. In a syringe having a non-metallic barrel, a groove adjacent the end thereof, a band fitting in said groove, a ferrule fitting 40 over said band, and means securing the ferrule and the band.
2. In a syringe having a non-metallic barrel, a groove adjacent the end thereof, a band fitting in said groove, and a ferrule soldered to said band.
3. In a syringe having a non-metallic barrel, a groove adjacent the end thereof, a band fitting in said groove, and a ferrule overlying and soldered to said band.
4. A syringe comprising a non-metallic barrel, a groove adjacent the end of the barrel, an end fused to the barrel, a ferrule 45

covering the end and soldered to the band, a plug having a ground fit in the barrel, and a nozzle passing through the plug. 55

5. A syringe comprising a non-metallic barrel, a groove adjacent the end of the barrel, a band seated in said groove, a ferrule secured to said band, a piston sliding in the barrel, and a latch carried by the ferrule 60 and movable to a position to stop the piston before the latter disengages from the barrel.

6. A syringe comprising a non-metallic barrel, a groove adjacent the end of the barrel, a band seated in the groove, a ferrule secured to said band, a piston sliding in the barrel, and an arched latch mounted on the ferrule and movable to engage and stop the piston when it is about to leave the barrel. 65

7. In a syringe, the combination with an open ended barrel, of a removable piston therein, a finger rest on the end of the barrel, a latch pivoted to said finger rest and movable about the same to and from a position preventing removal of the piston from the barrel and a position permitting removal of said piston. 70

8. In a syringe, the combination with a non-metallic open ended barrel provided with a groove adjacent its rear end, of a piston in said barrel, a band fitting in said groove, a finger rest secured to said band, and a latch pivotally secured to said finger rest in a manner to permit or prevent removal of the piston from the barrel. 80 85

9. A syringe comprising a non-metallic barrel, and end fused therein, a plug having a ground fit, and a nozzle passing through the plug and the end.

10. A syringe comprising in combination a non-metallic barrel, a non-metallic disc fastened thereto, a plug fitting within the barrel and adjacent the disc, a nozzle extending through the plug and through the disc and having its inner end enlarged to prevent its removal through said plug, and a clamping means in cooperation with said nozzle and disc to retain said plug and nozzle in cooperation with said disc. 90 95

Signed at New York city in the county of New York and State of New York this 8 day of March A. D. 1920. 100

ROBERT E. KLETT.
